H. R. Noll,

Sash Fastener.

No 9,649.

Patented Apr. 5, 1853.

UNITED STATES PATENT OFFICE.

HENRY R. NOLL, OF LEWISBURG, PENNSYLVANIA.

ARRANGEMENT OF SASH-FASTENERS.

Specification of Letters Patent No. 9,649, dated April 5, 1853.

To all whom it may concern:

Be it known that I, HENRY R. NOLL, of Lewisburg, Pennsylvania, have made certain new and useful Improvements in Sash-
5 Fasteners, of which the following is a de-
scription.

My invention and improvements consist
in so arranging the spring catch fastenings
for window sashes that the spring for the
10 upper sash may be commanded without in-
terference from the lower sash. That is to
say, if the lower sash is raised, the spring
of the upper sash can be managed without
dropping the lower sash.

15 In Figure 1, I have shown the rear side of
the plate and spring fastenings, in Fig. 5,
the front side of the same, in Fig. 2 a lon-
gitudinal section, of the same, in Fig. 3 a
20 transverse section, of the same, in Fig. 4 the
plate let in to the window frame and also
the spring roller in position. in Fig. 6 the
notches in the window sash.

The two spring fastenings, (consisting of
the spring bolts k , k' operated by the thumb
25 pieces a , a' through the medium of the con-
necting straps b , b'), are attached to one
plate in the following manner. Thumb
piece a is attached by its stem s to strap b ,
and thumb piece a' is attached by stem s'
30 to strap b' . The strap b' is hinged at h in
order on account of its length to insure
steadiness of motion. The stems s and s'
pass through suitable openings in the plate
35 p . The bolts k , k' are kept by the force of
the spiral springs projecting through and
beyond the plate p , so as to take into the
notches o in the upper and lower sashes.
The bolts are guided by their openings

through which they pass in plate p and also
by their stems r , r' passing through openings 40
in the gallows frames g , g' . The spring
roller is shown in Fig. 4 in position in the
upper sash where n exhibits a common flat
spring at the free end of which is a friction
45 roller m , the spring being let into a slight
mortise in the sash and the roller project-
ing; for the purposes above mentioned.

It will now be seen clearly that while the
lower sash is up or open, the upper sash may
be controlled and fixed in any desired posi- 50
tion by pressing upon the thumb piece a'
and seizing the sash with the hand from
above or under and behind the lower sash.

What I claim as my invention in window
sash fastenings, is— 55

1. Arranging the spring catch fastenings
for the upper and lower sash about the mid-
dle of the frame in such manner that the
upper sash can be managed, or fastened and
unfastened without interference from the 60
lower sash substantially in the manner here-
in set forth.

2. I claim the particular arrangement of
the attachments on the one plate, of the two
spring fastenings, said arrangement con- 65
sisting in the swing bar b' (through which
the spring bolt k' of the upper sash is oper-
ated), with its hinge joint in the rear of the
spring bolt k , and the bar b and bolt k of the
lower sash by which I gain economy of 70
room and a cheap and efficient action upon
the two sashes, in the manner set forth.

HENRY R. NOLL.
